UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

BREAST-CUTTING OPEN-DITCH EXCAVATOR.

1,175,926.

Specification of Letters Patent. Patented Mar. 21, 1916.

Application filed May 12, 1913. Serial No. 766,986.

To all whom it may concern:

Be it known that I, MORTON G. BUNNELL, a citizen of the United States of America, and resident of Chicago, Cook county, Illinois, have invented a certain new and useful Improvement in Breast-Cutting Open-Ditch Excavators, of which the following is a specification.

My invention relates to excavators in general, but more particularly to excavating machines of that kind in which the excavating apparatus operates transversely of the ditch, and especially those in which means are provided for cutting away the dirt on the breast of the ditch, as well as at the opposite sides thereof, whereby it is not necessary to raise and lower the excavating apparatus during the forward progress of the ditch.

Generally stated, the object of my invention is to provide a novel and highly efficient breast cutting open ditch excavator of the foregoing general character.

The special objects are to provide a novel and improved construction whereby the excavating apparatus not only works on the breast of the ditch, cutting away the dirt thereon as the machine travels forward, but also cuts away the dirt at opposite sides of the ditch, thereby insuring a sloping bank at each side thereof, as the machine travels along; to provide a novel and effective construction and arrangement whereby the breast cutting devices are separate and distinct from the means for taking up and carrying away the dirt, the said means consisting of an endless series of buckets traveling on the runway, the latter extending transversely of the ditch, and serving to determine the cross sectional contour thereof; and to provide certain details and features of construction and combinations tending to increase the general efficiency and serviceability of a breast cutting open ditch excavator of this particular character.

To the foregoing and other useful ends, my invention consists in matters hereinafter set forth and claimed.

In the accompanying drawings,—Figure 1, is a front elevation of an excavator embodying the principles of my invention. Fig. 2, is an enlarged front elevation of the breast cutting knives shown in Fig. 1, showing the runway and the buckets thereof, as

well as the breast cutting wheel, in dotted lines. Fig. 3, is a side elevation of the parts shown in Fig. 2, showing the runway in vertical section, and illustrating the manner in which the wheel operates on the breast of the ditch. Fig. 4, is an enlarged detail section on line 4—4 in Fig. 2.

As thus illustrated, my invention comprises a wheel I of a size to sink entirely into the ditch, having cutters i on the working face thereof and the sloping banks of the ditch are made by the swinging knives J, whereby a ditch of the required character is produced, notwithstanding the comparatively small diameter of the wheel. The said knives are disposed at opposite sides 65 of the wheel, and are provided with shanks or stems j, which are in turn secured to the plate or support K, which latter is disposed at the top of the wheel. This plate K swings about an axis k mounted in any suitable manner, and is provided with a radial slot k¹, which latter is engaged by a crank pin k², carried by the crank k³, which latter is operated in any suitable manner. The shanks or stems j are suitably mounted in sleeves j¹ secured to the plate K, and are held in such manner that each stem is capable of sufficient oscillation to permit the blades J, which are double edged, to operate first in one direction and then in the other. In other words, each blade turns at an angle to cut the dirt on the breast of the ditch, when the plate K swings in one direction, and when the said plate reverses its motion and starts in the opposite direction 75 each blade then turns at an angle to bring the opposite cutting edge thereof into use. Thus the said knives J are operated to cut the dirt away at each side of the wheel, as the machine is slowly moved forward.

The coöperation of the wheel I and the knives J results in the formation of a ditch having a rounded bottom and sloping sides. In this case, however, the slope of the sides is determined, more or less, by the runway 100 L which is disposed back of the wheel I, and which may be of any suitable construction. Buckets M are arranged to travel on said runway, whereby the dirt is taken up and carried away. With this arrangement, the buckets do not work on the breast of the ditch, as the wheel I and the knives J are ahead of the buckets, and thus the latter

simply work on the sides and bottom of the ditch. It will be seen that the said knives J swing back and forth immediately behind the wheel I, thus shearing off the corners 5 or overhang of the ditch, and causing the latter to have flat and sloping sides. These sides are afterward smoothed, and rendered perfectly flat, by the buckets M, which travel around the triangular shaped runway L, 10 the latter being pivoted at L to the brackets L, which are secured to the side of the body N of the excavator. Any suitable power transmitting connection can be employed for operating the wheel I and knives J, such as 15 the sprocket connection K, and this may in turn be driven by any suitable connection with the link belts upon which the buckets are mounted, or in any other suitable manner. The shafts α and β of the said sprocket 20 gearing can be mounted in suitable bearings on the said runway. Said shaft α is, of course, also the supporting shaft for the wheel. The runway L, and the excavating apparatus and devices carried thereby, can 25 be raised and lowered by any suitable means, such as the pulley and cable arrangement O shown in Fig. 1, or in any desired manner. The body N is preferably mounted on caterpillars n, or on other suitable traction devices, whereby the machine is adapted to 30 travel parallel with the ditch at one side thereof, and with the runway and excavating apparatus in position to move forward and form the ditch without being raised 35 out of the ground. The dirt taken up by the buckets may be carried away in any suitable manner, as by the aprons or conveyers P and Q, whereby a spoil bank is formed at one side of the ditch, behind the machine, 40 or by means of which the excavated dirt may be loaded into wagons and carried away.

The wheel I has a tunneling action, inasmuch as it bores a round hole in the ground, 45 and if not combined with other elements would not make a ditch when the runway is lowered to full working depth. Of course, and should the said runway be lowered only to an extent sufficient to bring the axis of 50 said wheel to the surface of the ground, then a ditch would be cut by the wheel alone; but with the diameter of the wheel substantially the same as the maximum depth desired for the ditch, the said wheel is not 55 capable of cutting a trench suitable for this purpose. It is for this reason, therefore, that the knives J are arranged to cut away the overhang of the tunnel, practically as fast as the round hole or tunnel is formed, 60 and this operation is of such character that the overhang is cut away for some distance back from the sides of the round hole or tunnel, thereby sloping the sides of the ditch approximately in accordance with the angles 65 of the side portions of the runway. When

the buckets behind the knives J are moved forward this operation serves to cut away the upper and lower ridges left by the said knives, whereby the sides of the ditch are rendered smooth or flat, in the manner illustrated. In one sense, therefore, the general operation of making the ditch involves primarily a tunneling operation followed very closely by the cutting away of the overhang to convert the tunnel into a ditch suitable 70 for drainage purposes, the sides or banks being given the angle of repose, or substantially so, by the means which follow in rear of the tunneling wheel.

I do not limit myself to the exact construction shown and described.

What I claim as my invention is:

1. A breast cutting open ditch excavator comprising a wheel arranged to rotate about an axis extending longitudinally of the ditch, provided with means for cutting the dirt away on the breast of the ditch, an up-and-down movable support for said wheel, traveling devices adjacent the wheel for taking up the dirt, mechanism for driving the wheel, means for moving the wheel ahead in the direction of the axis thereof, means for operating on the breast of the ditch at each side of said wheel to slope the banks in accordance with the angles of operation of said devices.

2. A breast cutting open ditch excavator comprising a wheel mounted to rotate about an axis extending longitudinally of the ditch, provided with means for cutting the dirt away on the breast of the ditch, devices adjacent the wheel for taking up the dirt, mechanism for driving the wheel, means for moving the wheel ahead in the direction of the axis thereof, swinging knives for cutting dirt from the breast of the ditch at each side of said wheel, and means for operating said knives back and forth.

3. A breast cutting open ditch excavator comprising a wheel mounted to rotate about an axis extending longitudinally of the ditch, provided with means for cutting the dirt away on the breast of the ditch, devices adjacent the wheel for taking up the dirt, mechanism for driving the wheel, means for moving the wheel ahead in the direction of the axis thereof, and knives for cutting away the dirt at each side of the wheel, each knife being double edged and self adjusting to automatically bring the two edges alternately into use.

4. A breast cutting open ditch excavator comprising a wheel arranged to rotate about an axis extending longitudinally of the ditch, provided with means for cutting the dirt away on the breast of the ditch, an up-and-down movable support for said wheel, traveling devices adjacent the wheel for taking up the dirt, mechanism for driving the wheel, means for moving the wheel ahead

in the direction of the axis thereof, and cutting devices geared to the wheel for cutting away the dirt on the breast at each side thereof.

5. A breast cutting open ditch excavator comprising a wheel provided with an axis extending longitudinally of the ditch centrally thereof, having means for cutting away the dirt on the breast of the ditch, means for driving the said wheel, and means for crowding the wheel forward in the direction of the axis thereof, a runway behind said wheel, serving to determine the cross sectional contour of the ditch, means 10 on said runway for carrying away the dirt, and means for operating on the breast of the ditch at each side of said wheel.

6. A breast cutting open ditch excavator comprising a runway extending across the 20 path of the ditch, and movable up and down in the ditch, means on the runway for cutting a section of ditch with sloping sides, as the runway moves downward, means traveling on the ground surface for moving 25 the excavator along after the said runway reaches the desired depth for the ditch, devices for operating on the breast of the ditch while the excavator moves forward, said devices including a wheel provided with cutters, and other cutters operating at each 30 side of said wheel.

7. A breast cutting open ditch excavator comprising a runway extending across the path of the ditch, and movable up and down 35 in the ditch, means on the runway for cutting a section of ditch with sloping sides, as the runway moves downward, means traveling on the ground surface for moving the excavator along after the said runway reaches the desired depth for the ditch, devices for operating on the breast of the ditch while the excavator moves forward, said devices including a cutting wheel sup- 40

ported by said runway, and cutters for sloping the banks at each side of said wheel.

8. A breast cutting open ditch excavator comprising a runway extending across the path of the ditch, and movable up and down in the ditch, means on the runway for cutting a section of ditch with sloping sides, as 50 the runway moves downward, means traveling on the ground surface for moving the excavator along after the said runway reaches the desired depth for the ditch, devices for operating on the breast of the ditch while 55 the excavator moves forward, said devices including a tunneling wheel, and means for cutting away the overhang of the tunnel in rear of said wheel.

9. An excavator comprising a tunneling 60 wheel, means operating in conjunction therewith for cutting away the overhang of the tunnel in rear of said wheel, thereby to shape the sides and convert the tunnel into a ditch, and an up-and-down movable support for said wheel and means.

10. An excavator comprising a tunneling wheel, means in conjunction therewith for cutting away the overhang of the tunnel in rear of said wheel, to convert the tunnel into 70 a ditch, said means operating to slope the sides of the ditch, and devices for taking up the dirt and smoothing the sides of the ditch behind said means.

11. An excavator comprising a tunneling 75 wheel, means in conjunction therewith for cutting away the overhang of the tunnel in rear of said wheel, to convert the tunnel into a ditch, and devices for taking up the dirt behind said means.

Signed by me at Chicago, Illinois, this 80
30 day of April, 1913.
